(57) CLAIM

The ornamental design for a golf club head, as shown and described.

DESCRIPTION

This application is also related to the following concurrently filed U.S. applications, each of which is also entitled Golf Club Head: Ser. No. 29/311,345; Ser. No. 29/311,350; Ser. No. 29/311,351; Ser. No. 29/311,349; Ser. No. 29/311,357; and Ser. No. 29/311,358.

FIG. 1 is a front view of a golf club head showing our design; FIG. 2 is a rear view thereof;

FIG. 3 is a right side view thereof;

FIG. 4 is a left side view thereof;

FIG. 5 is a top plan view thereof; and,

FIG. 6 is a bottom plan view thereof.

The broken lines in FIGS. 1–6 represent unclaimed environmental structure.
